CLAIM

The ornamental design for a housing for a retractable animal leash, as shown.

DESCRIPTION

FIG. 1 is a perspective view of a housing for a retractable animal leash according to my new design;

FIG. 2 is a front elevational view of the housing for a retractable animal leash, the rear elevational view being a mirror image thereof;

FIG. 3 is a right side elevational view of the housing for a retractable animal leash illustrated in FIG. 2;

FIG. 4 is a left side elevational view of the housing for a retractable animal leash illustrated in FIG. 2;

FIG. 5 is a top plan view of the housing for a retractable animal leash; and,

FIG. 6 is a bottom view of the housing for a retractable animal leash.
